UNITED STATES PATENT OFFICE

2,230,603

LIQUID DISPENSING APPARATUS

George L. Tone, Wallingford, and George A. Smith, Philadelphia, Pa., assignors to Sun Oil Company, Philadelphia, Pa., a corporation of New Jersey

Application April 2, 1938, Serial No. 199,640

1 Claim. (Cl. 221—95)

The present invention relates to fluid dispensing apparatus and more particularly it relates to gasoline pumps of the type ordinarily used at service stations.

5 In order to prevent fraud in the operation of such pumps it is desirable that means be provided whereby suitable warning will be given to the customer if the indicating device on the pump was not set at zero when delivery of gasoline is 10 started.

Most of the existing devices for accomplishing this result consist of an interlock between the "zeroizing" device used to return the register to zero and the switch for starting the motor which 15 operates the pump, or of an interlock between the "zeroizing" device and a valve in the liquid dispensing outlet. In all these "zeroizing" devices it is impossible, once the nozzle has been returned to the hook at the end of one dispensing 20 operation to again deliver gasoline after the nozzle has been removed from the hook at the start of a succeeding dispensing operation before the register has been reset to zero. While this prevents the station operator from having a 25 register indicate a greater quantity of liquid than actually has been dispensed to a given customer, it has a disadvantage in that when the operator hangs up the hook and a customer then decides that he wishes more gasoline the operator must 30 reset his register to zero before any further quantity of gasoline can be dispensed so that in this case the final reading of the register is not the total quantity of gasoline dispensed but is merely the amount which the customer decides he 35 wishes added to that first delivered to him.

It is therefore an object of the present invention to provide a zero interlock for gasoline pumps which is positive in operation and simple in construction and which will give ample warning 40 to the customer in case the pump has not been set to zero before delivery of gasoline is started, but which nevertheless will permit the delivery of additional quantities of gasoline when necessary without the necessity of resetting the 45 pump to zero.

A further object of our invention is to provide a signal device the operation of which is controlled directly by the position of the indicating device. Other and further objects will be apparent as the description progresses.

Referring to the drawing—

Fig. 1 is a representation of a gasoline pump in elevation.

Fig. 2 is a detail of the numeral wheels and sig-

nal operating mechanism embodied in the present invention.

Fig. 3 is an enlarged detail of the signal operating mechanism and

Fig. 4 is a sectional view taken on line 4—4 of Fig. 3.

As shown in the drawing the numeral 1 designates the casing of an ordinary service station pump which consists of a motor operated pump (not shown) by means of which liquid is drawn 10 from a reservoir, generally an underground tank, and forced through a meter 2 and thence through a hose 3 to a trigger operated dispensing nozzle 4. The amount of gasoline dispensed is measured 15 by the meter 2 and some function of the quantity of gasoline dispensed, either the number of gallons dispensed or the cost of the same, is computed and registered by the computor unit 5 operated by the meter shaft, the computor unit 5 having suitable mechanism for actuating a plurality of numeral wheels 10 which are visible 20 through a window in the pump casing and which may be reset to zero at the completion of a delivery operation by turning the zeroizing crank 26. 25 The exact details of the construction of the pump and its various elements are not shown since these form no part of the present invention per se, the pump merely being a standard service station gasoline pump and the various elements 30 being arranged in the common and well known manner therein.

A hook 6 extending through the pump casing is provided for receiving the nozzle 4 when not in use. This hook is pivoted on a pin 7 and two lugs 8 and 9 are provided on its inner end. A mercury switch 25 is mounted on hook 6 and is adapted to close the electric circuit through wires 23 and 24 leading to a motor for operating the pump thus initiating the operation of the pump 40 when the outer end of the hook 6 is raised.

A plurality of numeral wheels 10 are shown. These wheels are operated by the computor mechanism from the meter and indicate some function, either the price or the gallonage, of the 45 liquid dispensed through the nozzle 4 as heretofore stated. The operating mechanism for these wheels is not shown since such mechanism is well known in the art. Two bars 11 and 12 are supported and pivoted on a rod 13 secured within 50 the pump casing. Both of these bars are adapted to be contacted by the inclined lug 8 and the bar 11 is adapted to be contacted by the inclined lug 9. A hole 14 is provided at a pre-determined position in each of the numeral wheels 10 so that

when the zero indicia on each of these wheels is visible through the window provided for this purpose in the pump casing, the holes 14 in wheels 10 are opposite and in registry with pins 5 15 secured to bar 11. The bar 11 is pressed inwardly by spring 16 secured to rod 13 and has an upstanding projection 17 thereon which is adapted to contact the bar 12. A flag 18 preferably of dark colored transparent material is pivoted on a pin 19 and is adapted to swing down so as to cover the window through which the wheels 10 are visible. The flag 18 is so positioned that it is adapted to be supported by inner end of hook 6 or by an upstanding projection 20 on bar 12. A mercury switch 21 is secured to flag 18 and is adapted to close the circuit to an alarm bell 22 when the flag is down.

The operation of the device will now be described in detail. As shown in the drawing, the nozzle 4 is on hook 6 and therefore the outer end of the hook is in its lowermost position while the inner end is in its uppermost position. With the hook in this position the flag 18 is supported in its raised position by end of hook 6 and the lug 8 contacting bars 11 and 12 has swung these bars outwardly so that the projection 20 on bar 12 is removed from under the flag 18 and pins 15 on bar 11 are held away from the wheels 10. Assuming that it is now desired to deliver gasoline 20 the attendant must remove the nozzle 4 from the hook 6 and push the outer end of hook 6 upwardly so as to close the circuit through lines 23 and 24 and mercury switch 25 on the hook to the motor operating the pump. Raising the outer end of hook 6 will of course lower the inner end of the hook and since the bar 11 is pressed inwardly by spring 16 the bar 11 will tend to slide in along inclined lug 8 and if the numeral wheels 10 are in zero position, the pins 15 on bar 11 25 will enter the holes 14 in wheels 10 and therefore the bar 11 will swing completely in and upstanding projection 17 thereon will press against bar 12 and swing this inwardly so that projection 20 thereon will be swung under the flag 18 and will support this flag in its raised position when the inner end of hook 6 has been completely lowered. As the inner end of the hook falls the inclined lug 9 thereon will contact bar 11 and push this bar outwardly thereby pulling the pins 15 30 35 out of the holes 14 and thus leaving the wheels free to be rotated. In the event that one or more of the numeral wheels 10 are not in zero position, it is apparent that one or more of pins 15 will not be in registry with corresponding hole 55 14 in these wheels, therefore, as the inner end of hook 6 falls the spring 16 will press the bar 11 inwardly, but is prevented from swinging completely in by the pins 15 contacting the face of the wheels 10 so that this bar does not swing in far enough for the projection 17 thereon to swing the bar 12 and thus swing the projection 20 there-

on under the flag 18 so that the flag 18 will now swing downwardly, since the support of the hook 6 is removed, and cover the window, thereby giving warning to the customer that the pump has not been set to zero before the motor is started. When the flag is in its lowermost position the circuit through the mercury switch 21 to the bell 22 is closed and therefore the bell will ring and give additional warning to both the customer and the attendant that the pump has not been set to zero. In order to remove the flag it will be necessary for the attendant to again pull down the outer end of hook 6 thereby raising its inner end and then move the numeral wheels to zero after which when the outer end of the hook is again raised the pins 15 in bar 11 may enter the holes 14 in wheels 10 and therefore as heretofore explained the projection 20 on bar 12 will be swung under the flag 18 and will hold this flag in its raised position. 10 15 20

From the foregoing description it is apparent that we have provided a device which will give a warning in the event that the indicating device on the pump is not cleared before delivery of gasoline is started and that we have provided such a device which is directly controlled by the position of the indicating means on the pump. While one specific embodiment of the present invention has been herein disclosed and described, it is apparent that various modifications may be made therein, and that it may be adapted to other types and styles of pumps without departing from the spirit of this invention or from the scope of the appended claim. 25 30 35

What we claim and desire to protect by Letters Patent is:

In a fluid dispensing apparatus having indicating mechanism for indicating some function of the fluid dispensed, means for returning said indicating mechanism to zero position, a casing surrounding said mechanism and having a window therein through which the progressive indicia displayed by said mechanism are visible, and a dispensing nozzle, the combination of a support for said nozzle pivotally mounted on said casing and adapted to assume one position when said nozzle is on said support and to assume a different position when said nozzle is off said support, a flag supported by said nozzle support when said nozzle is thereon, and adapted to fall and cover said window when said nozzle is removed from said support, auxiliary flag supporting means adapted to be moved into position to support said flag when said nozzle is removed from said support, and means associated with said indicating mechanism to prevent the operation of said auxiliary flag supporting means unless said indicating mechanism is in zero position. 40 45 50 55 60
